UNITED STATES PATENT OFFICE.

JOSHUA H. MARVIL, OF LAUREL, DELAWARE.

FRUIT-CRATE.

SPECIFICATION forming part of Letters Patent No. 374,799, dated December 13, 1887.

Application filed October 6, 1887. Serial No. 251,642. (No model.)

To all whom it may concern.

Be it known that I, JOSHUA H. MARVIL, a citizen of the United States, residing at Laurel, in the county of Sussex and State of Delaware, have invented new and useful Improvements in Fruit-Crates, of which the following is a specification.

My invention relates to fruit-crates used for carrying berries and similar small fruit in baskets.

It is the purpose of my invention to simplify and improve the construction of the crate, whereby the strips on the lid which are ordinarily used to confine the baskets in place may be utilized to fasten the lid upon the crate, thereby dispensing with the hinges, hasps, and locks heretofore used, and leaving a perfectly smooth top on the crate, free from all projecting irons or other device, thus permitting the piling of the crates one upon the other and in close order.

The invention consists in the several novel features of construction and new combinations of parts, hereinafter fully set forth, and definitely pointed out in the claims.

In the accompanying drawings, Figure 1 is a perspective view of the crate, the cover being raised to expose the under side. Fig. 2 is a plan view of the crate with the cover in place. Fig. 3 is a diagram showing the method of forming the angular corner-posts.

In the said drawings is shown the crate, which is composed of slats 2, arranged with intermediate spaces for purposes of ventilation. At each corner of the crate is a corner-post, 4, in the form of an angle-plate, said post embracing the angle of the crate and affording a secure fastening and support for the slats 2. Upon the two longer sides of the box or crate the slats 2 rise to the top of the corner-posts 4, and are flush therewith; but the end slats drop a little below the tops of said posts, and the ends of the cover or lid 5 rest upon said end slats, 2, and are nearly flush with the side slats, the intention being that the surface of the cover shall rise slightly above the edges of said side slats and the tops of the corner-posts. Upon the under side of the cover are fastened transverse strips 6, which rest upon the edges of the upper tier of baskets in the crate and confine them firmly

in place. Two of these strips upon each side of the center strip, 6^a, are prolonged to project beyond the edge of the cover, and may be rounded off to form dowels 7, which enter openings 8 in the side slat and near its upper edge. The central strip, 6^a, is prolonged in a similar manner, save that its end projects beyond the opposite edge of the lid, forming a dowel, 9, which is received by an opening, 10, formed centrally in the upper edge of the side strip, 2, lying opposite that containing the openings 8. To fasten the lid the dowels 7 are placed in the openings 8, and the opposite slats then sprung somewhat outward to permit the dowel 9 to enter the opening 10. The edge of the cover is cut away around the prolonged end of the central strip, as shown at 11, to permit the insertion of the fingers to spring the slat.

The corner-posts 4 are formed of solid wood, being sawed from a strip of scantling of proper size. Heretofore it has sometimes been customary to saw these posts out by making two cuts at right angles to each other, each cut parallel with one of the faces of the square strip. By this method, however, the portion of lumber within the angle was wasted. To remedy this objection I take a strip of lumber of proper thickness and length and of any width. In this strip I form a succession of saw-cuts, 12, at an angle of ninety degrees with each other and each at an angle of forty-five degrees with a central line drawn from edge to edge of the strip along the length of the strip. By this method each angular cut produces a finished post having its edges 4^a beveled without waste of lumber.

The method of forming the posts is not claimed herein.

By my invention I provide a simple and inexpensive construction for articles of this class, avoiding entirely the use of iron for hinges or fastenings which are constantly splitting off or being lost, besides forming inconvenient projections which interfere with the close piling of the crates.

By my invention a strong, handsome, and inexpensive crate is provided, having flush surfaces throughout except at the corner-posts, where the angles are beveled, so that a blow thereon will usually glance off without injury.

Heretofore packing-boxes have been used having covers which are locked by independent bolts shot simultaneously into sockets in the ends and one side of the box. Crates have 5 been made, also, having a cover resting on two opposite sides, which are cut down to bring the cover flush, or nearly so, with the remaining sides. I make no claim, broadly, to such forms of construction.

10 Having thus described my invention, what I claim is—

1. In a fruit-crate, the combination, with a body portion having openings on opposite sides near the edges, of a cover having parallel basket-confining strips upon its under side, one or more thereof having the ends prolonged beyond one edge of the cover and one or more of the remainder having the ends prolonged beyond the other edge of said cover to engage the openings in the sides of the crate, substantially as described.

15 2. In a fruit-crate, the combination, with a body portion having corner-posts and parallel sides flush therewith and provided with 20 openings near the edges, of end portions hav-

ing their edges lower than the sides to support the cover, and a cover having parallel basket-confining strips on the lower face, the end of one of said strips being extended beyond one edge of the cover and the ends of the adjacent strips being prolonged beyond the opposite edge of said cover to engage the openings in the sides, substantially as described.

3. The combination, with the crate-body composed of slats 2 and corner-posts 4, the upper edges of the end slats being cut down and the side slats having perforations 8 and 10 upon opposite sides, of the lid or cover 5, having cross-strips 6, whereof the central strip, 6^a, is prolonged beyond one edge, and other strips on both sides thereof are prolonged beyond the opposite edge to engage the openings 8 and 10, substantially as described.

35 In testimony whereof I affix my signature in presence of two witnesses.

JOSHUA H. MARVIL.
